ELECTRICAL STARTING AND IGNITING APPARATUS.

1,427,074.

Specification of Letters Patent. Patented Aug. 22, 1923.

Application filed July 6, 1921. Serial No. 282,682.

To all whom it may concern:

Be it known that JAKOB BONLI, a citizen of the Swiss Republic, residing at Obach, Solothurn, Switzerland, have invented certain new and useful Improvements in Electrical Starting and Igniting Apparatus, of which the following is a specification.

In internal combustion engines, especially motor vehicles, which are provided with an 10 electromotive starting device, it is an advantage to construct the service ignition machine in such a manner that it will give an igniting spark even at the lowest speed of rotation. For this purpose in magneto-igniting devices arrangements have been made 15 such that at the moment when the engine is to be started, the current is sent from a storage battery through a buzzer into the primary winding of the device.

This arrangement has, however, the drawback that the current which then flows in the primary winding of the device is a direct current, whereas the magneto generates 20 alternating current in its primary winding so that the current of the buzzer is flowing alternately in the same direction and in the opposite direction to the primary current of the device. The result of this is that the 25 lines of force in the core of the coil of the device are directed at one time in the same direction as, and at another direction to those of the permanent magnet, with in the latter case a weakening effect upon the magnet.

In order to avoid this drawback special 30 commutating devices have been employed comprising insulated segments and rubbing contacts. Such devices however cannot be applied to every igniting apparatus and they must be mounted in a particular manner dependent upon the polarity of the magnets relatively to the existing battery.

According to the present invention a starting igniting apparatus with automatic pole-selector is employed that can be applied readily to any installation. The essence of this improved apparatus consists 45 in this that the tongue of the buzzer which is employed is caused by the action of a constant field and of an alternating field produced by the ignition apparatus, to move 50 to one side or the other according to the position of the magnet in the igniting device, and that the buzzer contact is so arranged that a buzzer action takes place only 55 when the tongue moves to one side corre-

sponding to a position of the ignition device such that the current sent by the buzzer into the coil of the ignition device produces lines of force in the same direction in the magnetic circuit of the ignition device as does 60 the permanent magnet of the said device.

The alternating action of a constant and alternating field necessary for the saturation of the tongue may be produced by magnetizing the tongue by a current of constant 65 direction and causing it to move in the alternating field of the ignition device.

An example of a starting ignition device constructed and operating according to the invention is illustrated in the accompanying 70 drawing. In this arrangement the tongue *e* of the buzzer is permanently magnetized by the coil *g* connected by the lead *e* through a switch *p* to the battery *d*, and the said tongue moves at the same time in the leak- 75 age alternating field emanating from the yoke portion *g* of the magneto-ignition device. The buzzer contact *h* is so arranged that it is closed, and buzzer current will flow through the lead *i* in the primary coil *f* of 80 the magneto device when the magnet with the poles *N* and *S* in the magneto device has a position such that the lines of force sent by it through the yoke of the device have 85 the same direction as those that are generated by the buzzer current.

In the reversed position of the magnet *N* *S* the field emanating from the yoke portion has altered its direction, so that the tongue *e* is pulled down by the coil *b* and 90 the contact *h* remains broken and no buzzer current is produced.

A condenser for damping the sparks at the contact *h* is indicated as *m*; *r* is a rotating interrupter of the igniting device and 95 *n* is the short-circuiting device for putting the ignition out of action.

What I claim is:

1. Apparatus for igniting internal combustion engines including a storage battery, 100 a buzzer furnished with a tongue and a magneto ignition dynamo having a primary and a secondary winding, the tongue of the buzzer serving to make and break by means of a pair of contacts, a circuit including said 105 battery, said buzzer, and the primary winding of said magneto, a constant magnetic field and an alternating field energized by said magneto, the said fields being arranged to coact with the tongue of the buzzer in 110

such a manner that current flows in the said circuit only when the alternating field is in the same direction as the field generated by the current in said circuit.

5 2. Apparatus as claimed in claim 1, wherein the tongue of the buzzer is polarized unidirectionally by current from the storage battery and moves in the alternat-

ing field of a rotating magnet of the mag-

neto. 10 In testimony whereof I have signed my name to this specification.

JAKOB BOHLI.
